UNITED STATES PATENT OFFICE.

HUGH JOHN McINTYRE AND WALTER JESSE WAKEFIELD, OF WINNIPEG, MANITOBA, CANADA.

DESIGN FOR A GAME-BOARD.

55,482.

Specification for Design. Patented June 15, 1920.

Application filed September 3, 1918. Serial No. 252,497. Term of patent 14 years.

To all whom it may concern:

Be it known that we, HUGH JOHN McINTYRE and WALTER JESSE WAKEFIELD, both subjects of the King of Great Britain, residing at the city of Winnipeg, in the Province of Manitoba, Dominion of Canada, have jointly invented a new, original, and ornamental Design for a Game-Board, of which the following is the specification, reference being had to the accompanying drawing, forming part thereof.

The figure is a plan view of a game board showing our new design which embodies a game board having a plurality of alternately different colored squares, there being nine squares to the side and the same color of square in each corner and a blank space in the shape of a cross located at the center of the game board and comprising a space equal to five squares.

We claim:

The ornamental design for a game board as shown.

HUGH JOHN McINTYRE.
WALTER JESSE WAKEFIELD.
